Charles T. Brady

By Attorneys

UNITED STATES PATENT OFFICE.

CHARLES T. BRADY, OF DETROIT, MICHIGAN.

DESIGN FOR AN ILLUMINATED HAND MAGNIFYING GLASS.

Application filed May 31, 1927. Serial No. 22,254. Term of patent 14 years.

To all whom it may concern:

Be it known that I, CHARLES T. BRADY, a citizen of the United States, residing at Detroit, in the county of Wayne and State of Michigan, have invented a new, original, and ornamental Design for an Illuminated Hand Magnifying Glass, of which the following is a specification, reference being had to the accompanying drawing, forming part thereof.

Figure 1 is a plan view of an illuminated hand magnifying glass, and

Fig. 2 is a side elevation thereof.

I claim:

The ornamental design for an illuminated hand magnifying glass, as shown.

CHARLES T. BRADY.
